UNITED STATES PATENT OFFICE

JAMES FRASER, OF HILLCREST, EDGE MOOR, DELAWARE, ASSIGNOR TO SPEAKMAN COMPANY, OF WILMINGTON, DELAWARE, A CORPORATION OF DELAWARE

DESIGN FOR A COMBINATION SOAP DISH AND FAUCET

Application filed November 2, 1928. Serial No. 28,742. Term of patent 14 years.

To all whom it may concern:

Be it known that I, JAMES FRASER, a citizen of the United States, residing at Hillcrest, Edge Moor, in the county of New Castle and State of Delaware, have invented a new, original, and ornamental Design for a Combination Soap Dish and Faucet, of which the following is a specification, reference being had to the accompanying drawing, forming part thereof.

The figure is a perspective view of a combination soap dish and faucet, showing my new design.

I claim:

The ornamental design for a combination soap dish and faucet, as shown.

JAMES FRASER.
